ATTORNEY

UNITED STATES PATENT OFFICE.

ISAAC LEWIS, OF HAMILTON, ONTARIO, CANADA.

DESIGN FOR A PATTERN FOR SACK-COATS.

53,132.

Specification for Design.

Patented Mar. 25, 1919.

Application filed April 27, 1918. Serial No. 231,254. Term of patent 7 years.

To all whom it may concern:

Be it known that I, ISAAC LEWIS, a subject of the King of Great Britain, residing at Hamilton, in the county of Wentworth and Province of Ontario, Canada, have invented a new and original and ornamental Design for a Pattern for Sack-Coats, of which the following is a specification, reference being had to the accompanying drawing, forming part thereof.

I claim:

The ornamental design for a pattern for sack coats, as shown.

In testimony whereof I have affixed my signature.

ISAAC LEWIS.

Witness:

H. G. HENDRY.
